RAILWAY SIGNALING

Ralph R. Kemmerer, Swissvale, Pa., assignor to
The Union Switch & Signal Company, Swiss-
vale, Pa., a corporation of Pennsylvania

Application March 6, 1936, Serial No. 67,494

18 Claims.

(Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of three sections in the rear of an occupied section. Each distinctive control is effective to cause a corresponding aspect of the associated wayside signal whereby there is produced a three-block, four-indication, system of signaling.

I will describe several forms of apparatus embodying my invention, and will then point out 15 the novel features thereof in claims.

In the accompanying drawings, Figs. 1A and 1B are diagrammatic views which when placed end to end in the order named illustrate one form of apparatus embodying my invention. Fig. 20 2 is a diagrammatic view illustrating a modification of a portion of Fig. 1A, and also embodying my invention.

Similar reference characters refer to similar parts in each of the several views.

25 Referring first to Figs. 1A and 1B, the reference characters 14 and 15 designate the rails of a stretch of railway track along which traffic normally moves in the direction indicated by the arrows. These rails are divided by insulated joints 16 into a plurality of track sections W—X, X—Y, and Y—Z.

As here shown, each track section is divided by insulated joints 16 into at least two subsections 1T, 2T, 3T, 4T, etc. Each subsection is provided with a track circuit which includes a track battery 17 connected across the rails at one end of the subsection and a track relay, designated by the reference character TR with a prefix the same as the numerical prefix in the reference 40 character of the associated subsection, connected across the rails at the other end of the subsection.

To govern the passage of trains through the stretch of railway, a wayside signal designated by a suitable distinguishing reference character, 45 is provided for each track section. Each of these signals includes an upper unit U and a lower unit L. These units may take any one of several forms of signal mechanism such as semaphore, color light, search-light, or position light. As here 50 shown, each upper unit U is a semaphore arm capable of assuming a horizontal or "stop" position, a 45° or "caution" position, and a vertical or "proceed" position; and each lower unit L is a lamp capable of displaying a yellow light Y.

55 Operably connected with each semaphore arm

U is a contact 19, a contact 20, and a pair of pole-changing contacts 21 and 22. Contact 19 is in engagement with contact 23 at all times except when the semaphore arm is in the vertical position and contact 20 is in engagement with contact 24 only when the semaphore arm is in the vertical position. Pole-changing contacts 21 and 22 are in engagement with contacts 25 and 26, respectively, whenever the semaphore arm is in its 45° position or in its vertical position or at any point between these two positions, and are in engagement with contacts 27 and 28, respectively, whenever the semaphore arm is at any point below the 45° position.

Each semaphore arm U is provided with a lamp 15 E which when lighted provides supplementary color light indications corresponding to the positions of the associated semaphore arm.

For controlling the associated signal, each section is provided with a polarized signal control 20 relay and a neutral signal control relay designated by the reference characters H and J, respectively, each with a prefix the same as the reference character of the associated signal.

For controlling the associated relay H, each 25 section is provided with a polarized line circuit which includes a pair of line wires each of which is governed by the associated track relays. For governing the associated relay J, each section is provided with a neutral line circuit which includes another line wire governed by each of the associated track relays and one wire of the associated polarized circuit.

Each section is provided with a line battery 30 9 the terminals of which are designated by the reference characters BL and CL and each section is provided with an operating battery the terminals of which are designated by the reference characters BO and CO.

Each relay H is connected to the associated polarized line circuit over signal contact 19—23 40 of the associated signal. Each relay J is connected to the associated neutral line circuit over a front neutral contact and a normal polar contact of the associated relay H. Each relay J is 45 also provided with a branch path which includes its own front contact and signal contact 20—24 for connecting this relay to the associated neutral line circuit.

The signal pole-changing contacts 21 and 22 50 control the polarity of the polarized line circuit for the section next in rear and the relays H and J control the neutral line circuit for such section next in rear.

For controlling the signal lamps E and Y, each 55

section is provided with an approach lighting relay designated by the reference character ER with a prefix the same as the reference character of the associated signal. The relays ER 5 are connected in series with the polarized line circuit for the section next in rear and therefore are energized at all times except when that line circuit is opened. In other words, the approach lighting relays ER become released to energize 10 the associated lamp E and the control circuit for the associated lamp Y only when the section immediately to the rear becomes occupied by a train.

The relays H and J control the upper unit U 15 and the lower unit L of the associated signal in the following manner: When relay H is de-energized (see signal 13), both semaphore arm U and the lamp Y are deenergized so that signal 13 is displaying its semaphore arm in the horizontal position to indicate "stop". When the relay H is energized in the reverse direction (see signal 12), a caution circuit for the semaphore arm U of that signal is closed over a path which passes from terminal BO over front contact 29 25 of relay 12H, semaphore arm U, and front contact 30 of relay 12H to terminal CO. Semaphore arm U of signal 12, therefore, is in the caution position to indicate "approach next signal prepared to stop". When relay H is energized in the normal direction and relay J is deenergized (see signal 11), the caution circuit for semaphore arm U remains closed over front contacts 29 and 30 of relay 11H and a circuit is established for the lamp Y of the lower unit L of that signal. 35 This circuit passes from terminal BO over back contact 31 of relay 11ER, normal polar contact 32-33 of relay 11H, front contact 34 of relay 11H, back contact 35 of relay 11J, and lamp Y to terminal CO. Signal 11, therefore, is displaying 40 its upper semaphore arm U in the caution position and a circuit for lamp Y is established so that, when relay 11ER becomes released by a train approaching signal 11 in section W-X, this signal will display its semaphore arm in the 45 caution position over a yellow light to indicate "approach next signal at medium speed". When relay H is energized in the normal direction and relay J also is energized (see signal 10), the caution circuit for the upper semaphore arm U 50 will remain closed over front contacts 29 and 30 of relay 10H and a proceed circuit for the semaphore arm U will be closed over a path which passes from terminal BO over front contact 29 55 of relay 10H, front contact 36 of relay 10J, semaphor arm U, and front contact 30 of relay 10H to terminal CO. Signal 10, therefore, is displaying 60 its semaphore arm in the vertical position to indicate "proceed at normal speed". When the upper semaphore arm U of signal 10 attains its proceed position, signal contact 19-23 will become opened so that relay 10H will become released. In the meantime, signal contact 20-24 65 will become closed so that relay 10J will remain connected to the associated neutral line circuit over a branch path which includes signal contact 20-24 and front contact 37 of relay 10J. The caution and clear circuits for upper semaphore arm U will now be disconnected from the terminals BO and CO of the operating batteries and 70 will be connected directly to the polarized line circuit for the section W-X.

As here shown, a train K is indicated diagrammatically in the section immediately to the right of location Z. Consequently, both line circuits 75 for that section are opened so that both relays

13H and 13J are deenergized. When relay 13H is deenergized, the semaphore arm U is in its horizontal position.

With signal 13 in this condition, relay 12H is energized in the reverse direction over a circuit which passes from terminal BL of line battery 9 at signal 13 through relay 13ER, pole-changing contact 22-28 of signal 13, front contact 38 of relay 6TR, front contact 39 of relay 5TR, relay 12H, signal contact 19-23 of signal 12, front contact 40 of relay 5TR, front contact 41 of relay 6TR, and pole-changing contact 21-27 of signal 13 to terminal CL of battery 9.

When relay 12H is energized in the reverse direction so that the semaphore arm U of signal 12 is caused to assume its caution position, relay 11H is energized in the normal direction over a circuit which passes from terminal BL of battery 9 at signal 12 through relay 12ER, pole-changing contact 21-25 of signal 12, front contact 42 of relay 4TR, front contact 43 of relay 3TR, signal contact 19-23 of signal 11, relay 11H, front contact 44 of relay 3TR, front contact 45 of relay 4TR, and pole-changing contact 22-26 of signal 12 to terminal CL of battery 9.

When relay 11H is energized in the normal direction and relay 11J is deenergized so that the semaphore arm U of signal 11 is in the caution position, relay 10H is energized in the normal direction over a circuit which passes from terminal BL of battery 9 at signal 11 through relay 11ER, pole-changing contact 21-25 of signal 11, front contact 46 of relay 2TR, front contact 47 of relay 1TR, signal contact 19-23 of signal 10, relay 10H, front contact 48 of relay 1TR, front contact 49 of relay 2TR, and pole-changing contact 22-26 of signal 11 to terminal CL of battery 9; and relay 10J is energized over the circuit which passes from terminal BL of battery 9 at signal 11 through normal polar contact 50-51 of relay 11H, front contact 52 of relay 11H, back point of contact 53 of relay 11J, front contact 54 of relay 2TR, front contact 55 of relay 1TR, normal polar contact 56-57 of relay 10TR, front contact 58 of relay 10TR, relay 10J, front contact 48 of relay 1TR, front contact 49 of relay 2TR, and pole-changing contact 22-26 of signal 11 to terminal CL of battery 9.

As hereinbefore explained, when relay 10H is energized in the normal direction and relay 10J also is energized so that semaphore arm U of signal 10 is caused to assume its vertical position, the relay 10H becomes disconnected from its polarized line circuit but the relay 10J remains connected to its neutral line circuit so that the caution and proceed circuits for semaphore arm U are directly connected to the polarized line circuit. The polarized circuit for the section next in rear of location W, therefore, is energized in the normal direction over pole-changing contacts 21-25 and 22-26 of signal 10, and the neutral line circuit for such section next in rear is energized over front point of contact 54 of relay 10J. The signal (not shown) for the section next in rear of location W, therefore, will be displaying its normal proceed indication.

When the train K vacates the section immediately to the right of location Z, relay 12H will become energized in the normal direction so that relay 11J will become energized. Since relay 11H is already energized in the normal direction, signal 11 will then be caused to display the normal proceed indication.

From the foregoing explanation, it will be apparent that the signaling system embodying my

invention will normally require only the energy necessary to maintain semaphore arm U in the vertical position and to energize relay 10J. Since this energy is relatively small and since under

5 normal conditions the signals will be displaying the normal proceed indication for the greater portion of the time, it will be apparent that my system will be unusually economical in current consumption. This will result in a material reduction 10 in the cost of maintenance particularly when primary batteries are utilized as a source of current.

Referring next to Fig. 2, the signal and associated apparatus shown therein, when connected 15 in a system, will function to provide three-block, four-indication, signaling in a manner similar to that described for the signals and associated apparatus shown in Figs. 1A and 1B. The principal difference is in the type of signal utilized 20 and in the manner in which the signal control relays are controlled as well as in the manner in which the line circuits are governed by the signal control relays. As here shown, the signal comprises an upper unit U and a lower unit LA. The 25 upper unit U is a semaphore arm capable of assuming three positions identical to those described for the semaphore arms shown in Figs. 1A and 1B, and the lower unit LA is a semaphore arm capable of assuming a horizontal position 30 or a vertical position but not a 45° position.

The signal is controlled by the usual neutral relay J and by a polarized relay having a retained neutral characteristic and designated by the reference character HA.

35 The relay HA is directly connected to a polarized line circuit including a pair of line wires and the relay J is directly connected to a neutral line circuit including another wire and one wire of said pair of wires.

40 When the relay HA is deenergized, both semaphore arms U and LA are in their horizontal positions to indicate "stop" and the polarized line circuit to the rear is supplied with energy in the reverse direction over the back points of contacts 45 56 and 57 of relay HA.

When relay HA is energized in the reverse direction, semaphore arm U is energized over a caution circuit which passes from terminal B of a suitable source of energy through front contact 50 58 of relay HA and semaphore arm U to terminal C of the same source of energy; and the polarized line circuit to the rear is supplied with current in the normal direction over the front points of contacts 56 and 57 of relay HA.

55 When relay HA is energized in the normal direction and relay J is deenergized, the caution circuit for semaphore arm U remains closed and a proceed circuit for the semaphore arm LA becomes closed over a circuit which passes from 60 terminal B through front contact 58 of relay HA, normal polar contact 59-60 of relay HA, and back point of contact 61 of relay J to semaphore arm LA and terminal C. The polarized circuit for the section next in rear is then energized in 65 the normal direction over front points of contacts 56 and 57 of relay HA and the neutral circuit for the section next in rear is then energized over normal polar contact 62-63 of relay HA, and front contact 64 of relay HA.

70 When relay HA is energized in the normal direction and relay J also is energized, the caution circuit for semaphore arm U remains closed and a proceed circuit for semaphore arm U is closed over a path which passes from terminal B 75 over front contact 58 of relay HA, normal polar

contact 59-60 of relay HA, and front point of contact 61 of relay J to semaphore arm U and terminal C.

Summing up for the signal and associated apparatus shown in Fig. 2, it will be seen that, when polarized relay HA is deenergized, both semaphore arms of the signal will assume the horizontal position and the polarized line circuit to the rear will be supplied with energy in the reverse direction. When the relay HA is energized in the reverse direction, semaphore arm U will assume the caution position and the polarized line circuit in the rear will be supplied with energy in the normal direction. When the relay HA is energized in the normal direction, semaphore arm U will assume the caution position, semaphore arm LA will assume the proceed position, the polarized line circuit in the rear will be supplied with energy in the normal direction, and the neutral line circuit to the rear also will be 20 energized. When the relay HA is energized in the normal direction and the relay J is also energized, semaphore arm U will assume the proceed position.

The relay HA is provided with a retained neutral characteristic so that tumble-down of the signal circuits to the rear will be avoided during pole-changing periods. For example, when the polarity of the polarized line circuit controlling relay HA is changed from the reverse direction to the normal direction, the front points of contacts 56 and 57 of relay HA do not become opened so that the energization of the line circuit to the rear is not disturbed.

Although I have shown herein but one signal 35 and associated apparatus in Fig. 2, it is understood that this signal and associated apparatus, when connected in a system, will function to provide three-block, four-indication signaling.

From the foregoing description of the apparatus 40 embodying my invention, it is apparent that I have provided a simple and reliable means for controlling a three-block, four-indication signaling system which requires but three line control wires between signals, and which requires direct 45 current energy only.

Although I have herein shown and described only a few forms of apparatus embodying my invention, it is understood that various changes and modifications may be made therein within 50 the scope of the appended claims without departing from the spirit and scope of my invention.

Having thus described my invention, what I claim is:

1. In combination, a section of railway track 55 having a track circuit including a track relay, a first line circuit for said section governed by said track relay, a second line circuit for said section also governed by said track relay, a polarized line relay governed by said first line circuit, a neutral line relay, means including a neutral and a polar contact of said polarized relay for connecting said neutral relay to said second line circuit, a signal for said section governed by said two line relays, and means governed in accordance with traffic conditions in advance of said section for reversibly governing said first line circuit as well as for governing said second line circuit.

2. In combination, a section of railway track 70 having a track circuit including a track relay, a first line circuit for said section governed by said track relay, a second line circuit for said section also governed by said track relay, a polarized relay governed by said first line circuit, a neutral relay governed by said second line circuit, a signal 75

for said section governed by said polarized relay and by said neutral relay, means for supplying said first line circuit with current of one polarity or with current of the other polarity according 5 to traffic conditions in advance of said section, and means governed by traffic conditions in advance of said section for supplying said second line circuit with current effective only when said first line circuit is supplied with current of a 10 particular polarity.

3. In combination, a section of railway track provided with a track circuit including a track relay, a pair of line wires each including a front contact of said track relay, a polarized relay connected to said pair of line wires, another line wire including a contact of said track relay, a neutral relay connected to said other line wire and to one wire of said pair of line wires, a signal governed 15 by said polarized and neutral relays, means governed in accordance with traffic conditions in advance of said section for supplying said pair of line wires with current of normal polarity or with current of reverse polarity, and means governed by traffic conditions in advance of said section 20 for supplying said other line wire with current of normal polarity only when the current in said one wire of said pair of wires is flowing in a particular direction.

4. In combination, a section of railway track, 30 a signal for said section, a signal control relay for said signal, a line circuit for controlling said relay, means for supplying current to said line circuit for energizing said relay, means effective when said relay is energized to cause said signal to display its normal proceed indication, means then effective to deenergize said relay, and means operably governed by the relay then effective to energize said signal directly from said line circuit.

40 5. In combination, a section of railway track, a signal for said section, a signal control relay for said signal, a line circuit for controlling said relay, means for supplying current to said line circuit for energizing said relay, means effective when said relay is energized to cause said signal to display its normal proceed indication, means including a contact operably governed by said signal for then deenergizing said relay, and a contact of said relay then effective to connect said signal to 50 said line circuit.

6. In combination, a section of railway track, a signal for said section, a signal control relay for said signal, a line circuit for controlling said relay, means for supplying current to said line circuit for energizing said relay, means effective when said relay is energized to cause said signal to display its normal proceed indication, means then effective to deenergize said relay, and means including a back contact of said relay for connecting said signal to said line circuit.

65 7. In combination, a section of railway track, a first signal control relay, a first line circuit for energizing said first relay, a second signal control relay, a second line circuit for energizing said second relay, means including a front contact of said first relay for connecting said second relay to the second line circuit, a signal for said section caused to assume its normal proceed 70 indication when both said relays are energized, means including a contact operably governed by said signal for deenergizing said first relay when said signal is displaying its normal proceed indication, means then effective to connect said second relay to the second line circuit, and an

other signal control circuit governed by a front contact of said second relay.

8. In combination, a section of railway track, a first signal control relay, a first line circuit for energizing said first relay, a second signal control relay, a second line circuit for energizing said second relay, means including a front contact of said first relay for connecting said second relay to the second line circuit, a signal for said section caused to assume its normal proceed indication when both said relays are energized, means including a contact operably governed by said signal for deenergizing said first relay when said signal is displaying its normal proceed indication, means including a contact operably governed by said signal and a front contact of said second relay for then connecting the second relay to the second line circuit, and another circuit governed by said second relay.

9. In combination, a section of railway track, 20 a first and a second signal control relay for said section, a first and a second line circuit for energizing said first and second relays, respectively, a signal for said section, means for causing said signal to display its normal proceed 25 aspect when both said relays are energized, means including a front contact of said first relay for connecting said second relay to the second line circuit, means for deenergizing said first relay and for energizing said signal from said 30 line circuit effective when said signal is displaying its normal proceed indication, and means then effective to maintain said second relay in the energized condition whereby another signal control circuit remains closed.

35 10. In combination, a section of railway track, a first line circuit and a second line circuit for said section, track circuit means for governing both line circuits, means governed in accordance with traffic conditions in advance of said section for supplying current of one polarity to said 40 first line circuit only or for supplying current of another polarity to said first line circuit only or for supplying current to said second line circuit simultaneously with the energization of 45 said first line circuit, a polarized relay governed by said first line circuit, a neutral relay governed by said second line circuit, and a signal for said section governed by said two relays.

50 11. In combination, a section of railway track, a first line circuit and a second line circuit for said section, track circuit means for governing both line circuits, means governed in accordance with traffic conditions in advance of said section for supplying current of one polarity to said first line circuit only or for supplying current of another polarity to said first line circuit only or for supplying current to said second line circuit simultaneously with the energization of 55 said first line circuit, a polarized relay governed by said first line circuit, a neutral relay governed by said second line circuit, a signal for said section including a first indication unit and a second indication unit, a circuit for said first unit including a front neutral contact of said polarized relay, another circuit for said first unit including a front neutral contact of said polarized relay as well as a front contact of said neutral relay, and a circuit for said second unit including a front neutral contact and a normal 60 polar contact of said polarized relay as well as a back contact of said neutral relay.

65 12. In combination, a forward section and a rear section of railway track, a signal for the forward section a pole changer operably gov- 70

erned by said signal, a polarized signal control relay and a neutral signal control relay both for governing said signal, traffic controlled means for governing said signal, traffic controlled means for governing said two relays, a first line circuit for the rear section including a pair of line wires and governed by said pole changer, a second line circuit for the rear section including another line wire as well as one wire of said first line circuit and governed by said two relays, and 10 a signal for the rear section governed by said first and second line circuits.

13. In combination, a forward section and a rear section of railway track, a polarized relay and a neutral relay, means governed in accordance with traffic conditions in advance of said forward section for governing said two relays, a pole changer governed by said polarized relay, a first line circuit for the rear section including a pair of line wires and said pole changer, a second line circuit including another wire and one wire of said first line circuit, means including neutral and polar contacts of said polarized relay for governing said second line circuit, and a signal for the rear section governed by said two line circuits.

14. In combination, a forward section and a rear section of railway track, a polarized relay for said section, means for reversibly governing said polarized relay in accordance with traffic conditions in advance of said section, a pole changer governed by said polarized relay, a polarized line circuit for the rear section reversibly governed by said pole changer, a neutral line circuit for the rear section governed by a front neutral contact and a normal polar contact of said polarized relay, and a signal for the rear section governed by said two line circuits.

15. A railway signal system comprising a plurality of successive sections of railway track, a polarized line circuit and a neutral line circuit for each section, means for each section effective when the associated polarized line circuit is deenergized to supply current of reverse polarity to the polarized line circuit for the section next in rear, means for each section effective when the associated polarized line circuit is energized in the reverse direction to supply such polarized line circuit in rear with current of normal polarity, means for each section effective only when the associated polarized line circuit is energized in the normal direction to supply such polarized line circuit in rear with current of normal polarity as well as to energize the neutral line circuit for the section next in rear, a polarized relay and a neutral relay for each section governed by the associated polarized and neutral line circuits, respectively, and traffic governing means for each section governed by the associated polarized and neutral relays.

16. A railway signal system comprising a plurality of successive sections of railway track, a polarized line circuit and a neutral line circuit for each section, track circuit means for each section for controlling the associated line circuit, means effective when one section is occupied to supply the polarized line circuit only for the section next in rear of such occupied section with current of one polarity, means then effective to supply the polarized line circuit only for the section second in rear of such occupied section with current of the opposite polarity, means then and only then effective to energize the neutral line circuit for the section third in rear of such occupied section as well as to supply current of said opposite polarity to the polarized line circuit for the section third in rear, and signaling means for each section governed by said two associated line circuits.

17. In combination, a stretch of railway track divided into a plurality of track sections, a polarized line circuit and a neutral line circuit for each section, track circuit means for each section for controlling the associated line circuits, means effective when one section is occupied to supply only the polarized line for the section next in rear of such occupied section with current of one polarity, means then effective to supply only the polarized line circuit for the section second in rear of such occupied section with current of the opposite polarity, and means then and only then effective to energize the neutral line circuit for the section third in rear of such occupied section as well as to supply current of said opposite polarity to the polarized line circuit for the section third in rear.

18. In combination, a stretch of railway track divided into a plurality of track sections, a polarized line circuit and a neutral line circuit for each section, track circuit means for each section for controlling the associated line circuits, means effective when one section is occupied to supply only the polarized line for the section next in rear of such occupied section with current of one polarity, means then effective to supply only the polarized line circuit for the section second in rear of such occupied section with current of the opposite polarity, means then and only then effective to energize the neutral line circuit for the section third in rear of such occupied section as well as to supply current of said opposite polarity to the polarized line circuit for the section third in rear, and signaling means for each section governed by the associated line circuits and capable of displaying at least three distinctive proceed indications.

RALPH R. KEMMERER.
